UNITED STATES PATENT OFFICE.

JOHN I. BELLAMY AND JOHN WICKS, OF CHICAGO, ILLINOIS, ASSIGNEES TO AUTOMATIC ELECTRIC COMPANY, OF CHICAGO, ILLINOIS, A CORPORATION OF ILLINOIS.

TELEPHONE TRUNKING SYSTEM.

Application filed April 5, 1922. Serial No. 549,730.

To all whom it may concern:

Be it known that we, JOHN I. BELLAMY and JOHN WICKS, both citizens of the United States of America, and both residents of 5 Chicago, Cook County, Illinois, have invented certain new and useful Improvements in Telephone Trunking Systems, of which the following is a specification.

The present invention relates to telephone 10 trunking systems in general, but is concerned more particularly with trunking systems of the type in which non-numerical trunk hunting switches are employed; and the principal object is the production of a 15 new and improved preselecting secondary trunk hunting switch for use in systems of the above character.

A special feature of the invention relates 20 to the production of new and improved circuit arrangements for a secondary switch, whereby the incoming test conductor is connected directly with the test wiper of the switch without intervening resistance coils or magnet windings, thus permitting a 25 primary switch to test the trunk line with which the wipers of the secondary switch are in engagement.

Another feature of the invention relates 30 to the provision of circuit arrangements, in a system which provides that at least one switch in each group of secondary switches will be standing on an idle trunk if there are any idle trunks, which prevent the secondary switches from hunting for idle 35 trunks when none are available.

The above pointed out objects, together 40 with others not specifically mentioned at this time, will be pointed out more fully hereinafter, reference being had to the accompanying drawings comprising Figs. 1 and 2, of which Fig. 1 is a secondary trunking layout showing a typical situation in which the improved secondary switch may be employed, while Fig. 2 shows by means 45 of the usual circuit diagrams a sufficient amount of the apparatus indicated in the trunking diagram, Fig. 1, to enable the improved secondary switch to be thoroughly understood and its utility appreciated.

50 Referring now particularly to Fig. 1, this diagram shows an arrangement of secondary switches by means of which a group of selector switches is given access on a particular level to a group of fifty out going trunks. The out going trunks are divided

into two sub-groups of twenty five trunks each, corresponding to the capacity of the secondary switches used, which are thus divided into two groups also. Only one trunk, however, in each secondary sub-group is indicated, which are the trunks leading out by way of the repeaters F and F'. The selector switches, so far as the level in question is concerned, are divided into eight groups, and since there are ten sets of contacts in a level there are eighty primary trunks which extend from the selector banks to secondary switches. These trunks are divided between the secondary sub-groups according to well known practice 65 in order to give each group of selectors access to each sub-group of secondary or out going trunks. For instance, primary trunks 1, 3, 5, 7, and 9 of the first group or the one in the upper left hand corner 70 of Fig. 1 extend to and terminate in secondary switches in the first sub-group, while the even numbered primary trunks 2, 4, 6, etc., of the first group extend to secondary switches of the second sub-group. 75 Similarly, the odd numbered trunks of the second primary group extend to secondary switches in the first sub-group while the even numbered trunk lines extend to switches in the second sub-group. The 80 same arrangement is followed in all the rest of the primary groups, although in order to save space the balance of the secondary switches have been omitted. The routing of all the other primary trunks, however, is 85 clearly indicated along the left hand margin. It will be understood that the grouping specified is by way of example merely, and that the precise arrangement may be 90 deviated from as circumstances require. 95

Referring now particularly to Fig. 2, the selector D shown therein is mechanically of the usual vertical and rotary type in which the bank contacts are arranged in horizontal rows or levels. This switch is one of 100 the group which has access to the first group of primary trunks Fig. 1.

The non-numerical secondary trunk hunting switch E is mechanically of the well known rotary type of switch in which the 105 wipers have no normal position and move in forward direction only. The circuits, however, are new and embody novel principles of operation, as will be pointed out subsequently.

The repeater F' is provided primarily to avoid the necessity of having three conductors in the associated inter-office trunk. It provides a holding circuit for the switches shown and repeats impulses over the outgoing side of the trunk.

The apparatus, having been described in general, will now be described in connection with a detailed description of its operation.

- 10 For this purpose it will be assumed that a call is extended to the selector D by way of the bank contacts 11-13, inclusive. Line relay 17 of the selector D energizes over the two line conductors in series in response to 15 the seizure of the switch and closes at armature 22 a circuit for release relay 18. Release relay 18, upon energizing, opens a point in the circuit of release magnet 26 and prepares a circuit for vertical magnet 27 20 at armature 24, and at armature 23 places ground upon the associated release trunk conductor, thereby establishing a holding circuit for the switches included in the connection back of the selector D.
- 25 In response to the calling of the next digit in the desired number, the circuit of line relay 17 is interrupted a corresponding number of times. Upon each deenergization of line relay 17, thereby produced, it 30 closes the following circuit of vertical magnet 27. From ground by way of the resting contact of armature 35 and said armature, armature 22 and its resting contact, armature 24 and its working contact, relay 35, 19, and vertical magnet 27 to battery.

By the operation of vertical magnet 27, the switch wipers 38-40, inclusive, are raised step by step until they stand opposite the desired level of bank contacts. Relay 19 is energized in series with vertical magnet 27 and, being slow acting, retains its armature 28 attracted throughout the vertical movement, and upon the closure of off normal contacts 34 closes a 45 circuit for stepping relay 20. Stepping relay 20, upon energizing, closes a locking circuit for itself independent of series relay 19 at armature 29, and at armature 30 prepares a circuit for rotary magnet 31. At 50 the end of the vertical movement, relay 19 deenergizes and completes the circuit of rotary magnet 31 at armature 28. Rotary magnet 31, upon energizing, advances the wipers 38-40, inclusive, into engagement 55 with the first set of contacts in the level opposite which they are raised, and at interrupter contacts 37 opens the circuit of stepping relay 20. Stepping relay 20, upon deenergizing, opens the circuit of rotary magnet 31 at armature 30. Rotary magnet 31 upon deenergizing, closes its interrupter contacts 37 again.

From this point the operation depends upon whether the trunk which terminates 60 in the first set of bank contacts is busy

or idle. If it is idle, switching relay 21 energizes immediately, but if it is busy switching relay 21 is short circuited by the ground potential which is present upon the test contact thereof, and stepping relay 20, upon 70 energizing, again closes a circuit for rotary magnet 31, whereupon the wipers are advanced into engagement with the next set of bank contacts. This alternate operation of stepping relay 20 and rotary magnet 31 continues until an idle trunk is reached. When an idle trunk is reached, which trunk it will be assumed is the one terminating in bank contacts 50-52, inclusive, switching relay 21, being no longer short circuited, 75 energizes in series with stepping relay 20. Stepping relay 20, however, does not energize at this time on account of the high resistance of switching relay 21. Upon energizing, switching relay 21 disconnects 80 ground from armature 22 of line relay 17 at armature 35, thereby opening the circuit of release relay 18; opens the test circuit and prepares the holding circuit at armature 33, thereby placing ground upon test 85 wiper 39 which ground makes the seized trunk busy immediately; and at armatures 32 and 36, disconnects the incoming line conductors 14 and 16 from the upper and lower windings of line relay 17 and extends them by way of wipers 38 and 40, bank contacts 50 and 52, line conductors 53 and 55, upper winding of relay 57, wipers 62 and 64, bank contacts 65 and 67, line conductors 68 and 70, and the left hand 90 windings of the repeating coil associated with the repeater F', to the upper and lower windings of line relay 71. Line relay 71, upon energizing, closes a bridge across the conductors of the associated inter-office 95 trunk at armature 74, whereupon the incoming switch (not shown) on the distant end thereof is prepared for operation in the usual manner. As a further result of the energization of line relay 71, it closes a 100 circuit for release relay 72 at armature 73. Release relay 72, upon energizing, closes a point in the circuit of chain relay 92 at armature 75, and at armature 76 establishes the usual holding circuit for the local 105 switches engaged in the connection such as the secondary switch E and the selector D. This holding circuit is established before the slow acting release relay 18 of the selector D has had time to deenergize.

In the secondary switch E, relay 57 is energized in series with line relay 71, and at armature 61 opens a point in the circuit of rotary magnet 58 and closes a locking circuit for itself, and at armature 60 first short circuits and then opens its own upper winding. Armature 60, it may be stated, is adjusted so as not to operate until after armature 61 has completed a locking circuit for the lower winding of the said relay 57.

As a result of the ground potential being placed upon release trunk conductor 54, a circuit is closed for relay 56. Relay 56, upon energizing, places a shunt around the 5 high resistance 85 at armature 59 for a purpose which will be explained hereinafter.

In response to the calling of the remaining digits of the desired number, the interruptions thereby produced in the circuit 10 of line relay 71 of the repeater F' are relayed to the associated inter-office trunk at armature 74, whereupon the connection is extended to the desired line in the usual manner.

15 Upon the termination of the ensuing conversation, the circuit of line relay 71 of the repeater F' is opened at the calling station. Upon deenergizing, line relay 71 opens the bridge across the associated inter-office trunk 20 conductors at armature 74, whereupon the connection extending ahead is released in the usual manner. As a further result of the deenergization of line relay 71, it opens the circuit of release relay 72 at armature 25 73. Release relay 72, upon deenergizing, opens a point in the circuit of chain relay 92 at armature 75, and at armature 76 removes ground from release trunk conductor 69, whereupon the repeater F' and the 30 switches D and E are accessible for common use. In the switch E, relays 56 and 57 deenergize in response to the ground potential being removed from release trunk conductor 69, and in the selector D, switch- 35 ing relay 21, upon deenergizing, closes a circuit for release magnet 26 at armature 35, by way of armature 22 and its resting contact, armature 24 and its resting contact, and off normal contacts 25. In re- 40 sponse to the resulting energization of release magnet 26, wipers 38-40, inclusive, are restored to normal position, the circuit of release magnet 26 being opened at off normal contacts 25 by the switch shaft when 45 the latter reaches normal position.

Upon referring to the circuit of secondary switch E, it will be seen that, since the test contact 51 thereof is connected directly with test wiper 63 thereof, the secondary 50 switch E tests busy in the banks of the selector D as soon as the trunk upon which its wipers are standing is seized. That being the case, the selector D, in searching for an idle trunk, passes over the secondary 55 switch E when the latter is standing on a busy trunk even though the switch E itself is not in use. The selector D continues to rotate until it finds a secondary switch which is standing upon an idle trunk, and 60 consequently, when an idle switch is found the connection is switched through to the repeater immediately, and no time is lost waiting for the secondary switch to find an idle trunk.

65 In a system of this kind it is desirable

that arrangements be provided so that at least one secondary switch, accessible to a particular selector or group of selectors, is standing upon an idle trunk at all times.

This result is accomplished in the present 70

case by bridging the normally open chain contacts in the circuit of the marginally 75

adjusted chain relay 88, which relay controls the trunk hunting movement of the 80

switches in this primary sub-group, with re- 85

sistances such as the resistances 85 and 86 90

which are shunted around the contacts con- 95

trolled by armatures 59 and 87. Armature 87 is assumed to be carried by a relay cor- 100

responding to relay 56 and associated with 105

a secondary switch which is accessible from 110

the same selectors from which the second- 115

ary switch E is accessible. There are ten 120

pairs of normally open contacts in the cir- 125

circuit of chain relay 88 and they are con- 130

trolled by the ten switches which are con- 135

nected with the ten trunks shown in the 140

upper left hand corner of Fig. 1. There 145

is a similar arrangement for the switches 150

connected with each of the other seven sub- 155

groups of primary trunks shown in Fig. 1. 160

When the trunks, upon which the wipers of 165

switches in the primary sub-group of trunks 170

to which the secondary switch E belongs, be- 175

come busy one by one until only one is left 180

idle, which trunk it will be assumed is the 185

one upon which the wipers of the secondary 190

switch E are standing, all the resistances 195

such as 85 and 86 are shunted by the as- 200

ociated relays, with the exception of re- 205

sistance 85. When this occurs, the marginally 210

adjusted chain relay 88 energizes in 215

series with resistance 85 and, upon so do- 220

ing, closes a circuit for relay 89. Relay 225

89, upon energizing, places battery upon 230

the stepping magnets of all the switches 235

in this primary sub-group, battery being 240

placed upon stepping magnet 58, for ex- 245

ample, at armature 94. When this occurs, 250

all the idle switches in this primary sub- 255

group whose wipers are standing upon busy 260

trunks start hunting for idle trunks. 265

Switch E, however, does not hunt at this 270

time for the reason that the circuit of 275

stepping magnet 58, although prepared at 280

armature 74, is not completed owing to the 285

fact that the trunk upon which it is stand- 290

ing is idle. As soon as an idle trunk is 295

found by one of the searching switches, the 300

relay thereof corresponding to relay 56 of 305

the switch E deenergizes and removes the 310

shunt from around the associated resistance. 315

For example, the shunt may be removed 320

from around the resistance 86 by armature 325

87 when the relay controlling the said ar- 330

mature 87 deenergizes. That being the case, 335

the marginally adjusted chain relay 88 de- 340

energizes and opens the circuit of relay 345

89 at armature 90. Relay 89, upon de- 350

energizing, removes battery from the step- 355

ping magnets of all switches in this primary sub-group, whereupon the trunk hunting ceases.

Assuming as before that relays 88 and 89 are energized with the result that the idle switches in this primary sub-group which are not standing upon idle trunks are hunting and assuming further that the wipers of the switch E are standing upon an idle trunk, 5 and that the switch E is seized by a selector, the selector D for example, a ground potential is placed upon test contact 51 at the same time that a bridge is closed across conductors 53 and 55. Consequently, stepping 10 magnet 58, having battery placed upon one terminal thereof by relay 89, starts to energize simultaneously with relay 57. Relay 57, however, owing to the fact that it has an armature which is lighter than the armature 15 of stepping armature 58 and also owing to the fact that armature 61 has a relatively weak spring tension, opens the circuit of stepping magnet 58 at armature 61 before the said magnet 58 has had time to energize. 20 Otherwise the results accompanying the seizure of the switch E are no different at this time than at any other time.

Assuming now that relays 88 and 89 are energized, that the switch E idle, and that 30 test wiper 63 is not standing upon an idle trunk, the wipers 62-64, inclusive, are advanced step by step in search of an idle trunk by the buzzer like action of the stepping magnet 58, the said magnet 58 being 35 supplied with battery by way of armature 94, and being supplied with ground by way of the grounded test contacts with which wiper 63 comes into engagement. Obviously wipers 62-64, inclusive, are stopped upon 40 the first trunk found to be idle regardless of the energized condition of relay 89. However, if some other switch finds an idle trunk before the switch E finds one, the latter stops hunting when relay 89 deenergizes regardless 45 of whether it has found an idle trunk or not.

It may be stated that relay 92 operates when all the repeaters in secondary sub-group #2 are busy or in other words when 50 all contacts such as those controlled by armatures 75 and 91 are closed. Upon operating, relay 92 removes battery from the lower five armatures of relay 89 and as a result the switches in this primary sub-group which 55 have access to secondary sub-group #2 are prevented from operating at this time in case relay 89 is energized. A similar chain relay is provided for the secondary sub-group #1 as is indicated by the conductors connected with the upper five armatures of 60 relay 89. The chain relays associated with the secondary sub-groups serve merely to prevent excessive mechanical wear and tear in the secondary switches by preventing them 65 from hunting at a time when no trunks are

available, which condition is very likely to arise in either of the sub-groups during a traffic peak. It will be understood that sufficient contacts are provided on relay 92 for each of the seven other primary sub-groups 70 and that the chain relay associated with the secondary sub-group #1 is similarly equipped.

This same arrangement can obviously be extended to any desired number of primary 75 sub-groups and to any desired number of secondary sub-groups without departing from the spirit of the invention.

The various features of the invention, having been described in the foregoing, will 80 now be pointed out in the appended claims.

What is claimed is:

1. In a telephone system, a non-numerical trunk hunting switch having a test wiper and line wipers which normally stand on the 85 corresponding contacts of a trunk, said switch having a test conductor and line conductors corresponding respectively to said wipers, said test conductor being connected directly with said test wiper, means for seizing said switch, and means controlled over said test conductor for preventing the seizure of said switch regardless of whether said switch is busy or idle when a busy potential is impressed upon the test contact upon 90 which said test wiper is standing.

2. In a telephone system, a non-numerical trunk hunting switch, said switch having a test wiper and line wipers which normally stand upon the corresponding contacts of a 100 trunk, said switch having a stepping magnet, said magnet having two terminals one of which is normally connected with said test wiper, means for operating the wipers of said switch in search of an idle trunk by 105 connecting the other terminal of said stepping magnet with a source of current, and a relay energized by current through one of said line wipers for disconnecting said stepping magnet when the switch is in use. 110

3. In a telephone system, a non-numerical trunk hunting switch having wipers which normally stand upon the contacts of a trunk, line conductors and a test conductor over which said switch may be seized, said switch 115 having a stepping magnet and a normally open circuit therefor, means for operating said wipers of said switch in search of an idle trunk by completing said circuit for said stepping magnet, and means operated by current flow over one of said line conductors in response to the seizure of said switch for opening a point in said circuit independent of said means for operating said wipers. 120

4. In a telephone system, a non-numerical switch, trunks accessible thereto, a stepping magnet for said switch, a circuit for said stepping magnet, means for causing said switch to hunt for an idle trunk by 130

closing the circuit of said stepping magnet, a relay operated in response to said trunks becoming busy, and contacts on said relay for opening the circuit of said stepping magnet when said trunks are busy so as to prevent the trunk hunting operation of said switch.

5. In a telephone system, a plurality of idle non-numerical trunk hunting switches, means for causing all of said switches while still idle to hunt for idle trunks, individual trunk testing means in each switch, and means for preventing the trunk hunting operation of said switches when all the trunks

15 accessible thereto are in use.

6. In a telephone system, two serially related automatic switches and a trunk line, bank contacts individual to the second switch accessible to the wipers of the first switch, 20 bank contacts individual to said trunk line engaged by the wipers of said second switch, and conductive metallic connections between the bank contacts and wipers of said second switch whereby the said first switch may be 25 operated to connect with said trunk line via said bank contacts and wipers independent of the operation of the second switch.

7. In a telephone system, two serially related automatic switches and a trunk line, a 30 test contact individual to the second switch accessible to the test wiper of the first switch, a test contact individual to said trunk line engaged by the test wiper of said second switch, and a direct metallic connection 35 without intervening resistance or magnet coils between the test contact and test wiper of said second switch, whereby the said first switch may be operated to test the said trunk line by way of said test contacts and test wipers.

8. In a telephone system, two serially related trunk lines, a switch individual to the first trunk line, bank contacts individual to the second trunk line engaged by the wipers 45 of said switch, a circuit established responsive to the seizure of said first trunk line, said circuit including the two talking conductors of both trunk lines in series, and a controlling relay in said switch included in 50 said circuit.

9. In a telephone system, two serially related trunk lines, a switch individual to the first trunk line, bank contacts individual to the second trunk line engaged by the wipers 55 of said switch, a circuit established responsive to the seizure of said first trunk line, said circuit including the two talking conductors of both trunk lines in series, a stepping magnet for said switch, and a relay 60 controlling said magnet and included in said circuit.

10. In a telephone system, two serially related trunk lines, a switch individual to the first trunk line, bank contacts individual to the second trunk line engaged by the wipers 65 of said switch, a circuit established responsive to the seizure of said first trunk line, said circuit including the two talking conductors of both trunk lines in series, a test conductor included in said first trunk line, a stepping magnet for said switch connected to said test conductor, and a relay included in said circuit and operated when the circuit is established to disconnect said stepping magnet from said test conductor.

75 11. In a telephone system, a trunk line terminating in an automatic switch, a second trunk line terminating in a repeater, a line relay in said switch, a line relay in said repeater, and a circuit including a talking 80 conductor of each trunk line for energizing both line relays in series.

12. In a telephone system, a trunk line terminating in an automatic switch, a second trunk line terminating in a repeater, a line 85 relay in said switch, a line relay in said repeater, wipers for said switch and bank contacts for said second trunk line through the medium of which said trunks are connected together when idle, and a circuit established 90 responsive to the seizure of the first trunk line for energizing both line relays in series.

13. The combination, with a plurality of switches each having a motor magnet, of a group of trunk lines accessible to said 95 switches, and a relay operated when all said trunks are busy for opening the battery connections to all said magnets.

14. The combination, with a plurality of switches each having a motor magnet, of a group of trunk lines accessible to said 100 switches, ground and battery connections for each magnet, means in each switch for opening the ground connection of its magnet, and means common to said trunk lines for opening the battery connections of all said magnets.

15. In a telephone system, an automatic switch, a trunk line terminating in said 110 switch and comprising two talking conductors and a test conductor, a stepping magnet for said switch normally connected to said test conductor, means for placing a potential on said test conductor when the trunk is taken for use, and a relay energized over a line conductor for disconnecting said magnet to prevent the same from energizing.

115 Signed at Chicago, Illinois, this 28th day of March 1922.

JOHN I. BELLAMY.
JOHN WICKS.
